UNITED STATES PATENT OFFICE.

LOUIS TAMPIER, OF BORDEAUX, FRANCE.

APPARATUS FOR DISPLAYING PUBLIC ANNOUNCEMENTS.

SPECIFICATION forming part of Letters Patent No. 373,951, dated November 29, 1887.

Application filed April 22, 1887. Serial No. 235,756. (No model.) Patented in England June 10, 1886, No. 7,818.

To all whom it may concern:

Be it known that I, LOUIS TAMPIER, at present residing at the Consulat Général de Turquie, Bordeaux, in the Republic of France, have 5 invented new and useful Improvements in Apparatus for Exhibiting Public Announcements or Advertisements, (for which Letters Patent of Great Britain have heretofore been granted to me, dated June 10, 1886, No. 7,818,) 10 of which the following is a full, clear, and exact description.

This invention relates to apparatus for exhibiting series of public announcements or advertisements carried by a band which is caused 15 to travel past an opening for the purpose of exhibiting the advertisements, &c., in succession; and the invention consists, essentially, of mechanism whereby an intermittent or a continuous motion is imparted to the band, and 20 whereby such motion is automatically reversed at the required times, in order that the display of the announcements, &c., shall be continued uninterruptedly. This mechanism comprises rollers acting alternately as "take- 25 up" and "let-off" rollers for the band and mechanism hereinafter described, whereby the direction of their motion is automatically reversed at the proper times in order to reverse the travel of the band. Two or more such 30 bands may be exhibited in the same case and may receive similar or different motions.

Reference is to be had to the accompanying drawings, forming a part of this specification, which represent an apparatus comprising two 35 bands, one receiving continuous and the other intermittent motion.

Figure 1 is a front elevation of the upper portion of the mechanism, the front of the casting being removed; and Fig. 1^a is a similar 40 view of the lower part, portions of the bands being broken away to show the mechanism. Fig. 2 is a side elevation of the upper portion, (the side of the case being removed,) showing the upper band and part of the chain-gear 45 actuating said band; and Fig. 2^a is a similar view of the lower portion, showing the lower band and its chain-gear, and also the escape- 50 ment and part of the chain controlling the upper or intermittently-moving band. Figs. 3 and 3^a are similar elevations of the opposite

side, showing more clearly the holding and guide rollers and the position of the bands thereon, and also the driving mechanism for the continuously-moving band. Fig. 4 is a front view of the clock-work; and Figs. 5 and 55 6 are a vertical section on line 22 and a side elevation, respectively, of Fig. 4. Figs. 6^a and 6^b are detail side views of the ratchet-wheel which is at intervals engaged with the ratchet-teeth on the periphery of the cam- 60 wheel. Fig. 7 is a detail side view and section of the clutch for reversing the mechanism. Fig. 8 is a detail side view of the chain-wheel for the intermittent band and of the device for controlling the said chain-wheel. Fig. 9 is an 65 edge view of the same. Fig. 10 is a side view of the mechanism at one end of one of the winding-rollers. Fig. 11 is a cross-sectional view of Fig. 10. Fig. 12 is a side view of the mechanism at the other end of the said roller. Fig. 7c 13 is a cross-sectional view of the same. Fig. 14 is a face view of the cam as laid down.

The same letters of reference indicate the same parts in all the figures.

The power by which the actuating mechanism of each band is driven is preferably a spring-barrel; but any other available prime mover may be employed.

A A^x are the two bands, receiving the one continuous and the other intermittent motion, 80 respectively. Their ends are attached to and wound on pairs of rollers a a a^x a^x, respectively, the bands passing over intermediate guide-rollers, and the portions of the bands distended between the guide-rollers being exhibited at openings a⁶ in the case within which the mechanism is contained. Certain of the guide-rollers act also as driving-rollers for the bands, and for this purpose they receive a positive motion.

B B^x are the endless chains by which the two sets of rollers for the bands A A^x are respectively actuated.

C is the driving mechanism for the band A, and C^x the mechanism for the band A^x.

The band A, attached to and wound on rollers a a, as above described, passes over or round guide-rollers d e f, as shown in Fig. 3^a, whereof the roller f receives motion from the clock-work C and transmits it through endless 100

chain B to the rollers *a a*. This roller *f* is roughened at the middle in order that it may assist in driving the band, which is pressed against the roughened part by a soft roller, *g*, 5 carried by a spring.

The clock-work C consists of a spring-barrel and train of wheels and pinions controlled by a fly, *h*, the wheel *i* of the train being in gear with the pinion *f'*, fastened on the end of 10 the roller *f*.

Upon the shaft of wheel *i* are two loose pinions, *k l*, in gear with the wheel *m* on the second-motion shaft, the one *k* gearing directly therewith and the other, *l*, gearing indirectly 15 through pinions *m' n* on a counter-shaft, *o*. Between these pinions *k l* the shaft of the wheel *i* is squared, and carries a clutch, *p*, formed of arms carrying pins *p'*, one or other of which comes into the path of an arm, *k'* or *l'*, fixed to 20 the pinions *k l*, whereby the shaft of wheel *i* is rotated in one or other direction, as the case may be. The clutch *p* is slid along the shaft to throw it into gear with one or other of the pinions *k l* and produce the desired reversal 25 of motion by a cam, *q*, (whose development is shown in Fig. 14,) acting on the pin *r* of a sliding rod, *s*, carrying a fork, *s'*, embracing the grooved boss of the clutch. The cam has a ratchet-toothed periphery, *q'*, and is driven 30 by a ratchet-pinion, *q*', (shown more clearly in Figs. 6^a and 6^b,) on the second-motion shaft *q*', the object of this form of gear being to permit of the position of the cam being adjusted to suit the position of the band, which is done 35 when the pinion is in such position that its teeth do not gear with the teeth on the cam, as shown in Fig. 6^b. The chain B runs on a chain-wheel, *b*, fast on the other end of roller *f*, and gears with similar chain-wheels, *c*, on 40 the axles of rollers *a*.

* *z*, &c., are guide-wheels. Each wheel *c* (see Figs. 11, 12, and 13) runs loose between collars on the boss of a ratchet-wheel, *t*, with which engages a pawl, *c'*, carried by the wheel 45 *c*. The ratchets are made friction-tight on the axle of the roller *a* by a spiral spring, *u*, compressed between the end of the roller *a* and the boss of the ratchet-wheel *t*, which is held in position by a cross-pin. At the opposite end 50 of each roller is another ratchet-wheel, *y*, made friction-tight by a spiral spring, *y'*, compressed between it and the end of the roller, a pawl, *y'*, mounted on a stationary support engaging with the ratchet-wheel *y*.

55 The parts of the clock-work C^x, which are similar to those of clock-work C, are distinguished by the same letters, with the addition of an asterisk, and need not be again described. The wheel *i*^x is, however, in this instance, a 60 chain-wheel, and drives the chain B^x, and the action of the clock-work C^x is controlled by an escapement actuated by the clock-work C through a shaft, *v*, Fig. 4, which is rocked periodically by a ratchet-toothed pin, *v'*, on the 65 second-motion shaft of clock-work C acting on an arm, *v''*, fixed to the shaft. The escapement consists of a spring-catch, *w*, Figs. 8 and 9,

pivoted to an arm, *w'*, fixed to shaft *v*, and engaging with a pin, *w''*, fixed to wheel *i*^x, and of a second catch, *x*, which comes in the path of the fly *h*^x, Fig. 2^a. By the motion of shaft *v* the catch *w* is first removed from the path of pin *w''*, the catch *x*, Fig. 2^a, meanwhile standing in the path of the fly *h*^x. When the arm *v''* falls off the point of a tooth of pinion *v'*, the 70 catch *x* is withdrawn also at the same time that catch *w* again comes in the path of pin *w''*, whereby the clock-work C^x is permitted to run until the wheel *i*^x has made one revolution, when it is again arrested. The chain B^x gears 75 with chain-wheels *c*^x, connected with the axles of rollers *a*^x by ratchet and friction gear similar to that before described. The chain also gears with a pinion fast on the end of the roller *f*^x, which is in this instance the upper guide-roller of the band. The roller *a*, which is for 80 the time being acting as the take-up roller for the band, is driven through the ratchet and friction gear at the driving end of said roller, the gear at the other end thereof then being 85 inoperative, and the necessary tension is applied to the band by the ratchet and friction gear at the opposite end of the other roller *a* (the let-off roller for the time being) acting as a brake for the said roller, the gear at 90 the driving end of the last-mentioned roller being then inoperative, and conversely when the direction of motion of the band is changed.

The object of using friction-gear between the driving chain wheels and the rollers *a* is 100 to prevent overwinding of the band and compensate for the varying diameter on which the band is wound.

Having now particularly described and ascertained the nature of the said invention and 105 in what manner the same is to be performed, I declare that what I claim is—

1. In an apparatus for exhibiting public announcements, the combination, with a band secured to rollers, of a motor and a driving-chain for rotating said rollers from the motor, a sliding bar in the motor-frame, a cam driven by the motor operating said bar, a double sliding clutch operated from said sliding bar, projections on said clutch, pinions provided 115 with arms with which the projections on the clutch can engage, and gearing for transmitting motion from said pinions to the wheels operating the driving-chain, substantially as set forth.

2. In an apparatus for exhibiting public announcements, the combination, with rollers, of a band secured at its ends to the rollers, ratchet-wheels on the rollers, toothed wheels mounted loosely on the shafts of the rollers, 125 over which to the wheels the driving-chain passes, spring-pawl on the toothed wheels and engaging with the ratchet-wheels on the shafts of the rollers, and spiral springs surrounding the shafts and holding the ratchet-wheels 130 friction-tight on the axles of the rollers, substantially as set forth.

3. The combination, with a roller and a band having one of its ends secured to the same, of

- a ratchet-wheel mounted on each end axle of the roller and held friction-tight on said axles by spiral springs surrounding the axles, a toothed wheel mounted loosely on the post of 5 the ratchet-wheel at one end of the roller, a driving-chain passing around said toothed wheel, a spring-bolt on said toothed wheel engaging with the ratchet-wheel, on the post of which the toothed wheel is mounted, and a 10 fixed pawl engaging with the ratchet-wheel at the opposite end of the roller, substantially as set forth.
4. In an apparatus for exhibiting public announcements, the combination, with two 15 motors, of two bands, each secured at its ends to separate rollers, power-transmitting gear for driving the two sets of rollers separately from two motors, a flier on each motor, and a lever controlled from one motor and adapted to engage a pin on a wheel of the other motor, and a rod 20 connected with said lever and adapted to engage a flier of the motor on the wheel of which the above-mentioned lever acts, substantially as set forth.
5. In an apparatus for exhibiting public announcements, the combination, with two mo-
- tors, of two bands, each secured at its ends to separate rollers, power-transmitting gear for 25 driving the two sets of rollers separately from two motors, a flier on each motor, a lever controlled by one motor and adapted to engage a pin on a wheel of the other motor, and a rod 30 connected with said lever and adapted to engage a flier of the motor on the wheel of which the above-mentioned lever acts, substantially as set forth.
- The foregoing specification of my improvements in apparatus for exhibiting public announcements or advertisements signed by me this 30th day of March, 1887.

LOUIS TAMPIER.
